UNITED STATES PATENT OFFICE

101,371

DESIGN FOR A LINK FOR WATCH BRACELETS, OR THE LIKE

Moad H. Le Marr, Los Angeles, Calif.

Application March 11, 1936, Serial No. 61,569

Term of patent 3½ years

To all whom it may concern:

Be it known that I, Moad H. Le Marr, a citizen of the United States, residing in Los Angeles, in the county of Los Angeles and State of California, have invented a new, original, and ornamental Design for a Link for Watch Bracelets, or the like, of which the following is a specification, reference being had to the accompanying drawing forming part thereof.

Fig. 1 is a top plan view; and

Fig. 2 is a side elevation of a link for watch bracelets, or the like, showing my new design.

I claim:

The ornamental design for a link for watch bracelets, or the like, as shown.

MOAD H. LE MARR.
